COMBINATION SAFETY-PILOT AND DIAPHRAGM VALVE

Delmar K. Everitt, Santa Susana, Calif., assignor to Itt
General Controls Inc., Glendale, Calif., a corporation
of California

Filed Jan. 13, 1964, Ser. No. 78,176

Term of patent 14 years

(Cl. D78—1)

FIG. 1.

FIG. 3.

FIG. 2.

FIG. 4.

FIG. 1 is a perspective view of a combination safety-pilot and diaphragm valve showing my new design;

FIG. 2 is an end view of the same;

FIG. 3 is a view showing the back of the same; and

FIG. 4 is a front elevational view of a modified form thereof, the design of FIG. 4 being otherwise the same as disclosed in FIGS. 1, 2 and 3.

I claim:

The ornamental design for a combination safety-pilot and diaphragm valve, as shown and described.
